SWITCH

Abraham S. Pinkus, New York, N. Y.

Application May 22, 1933, Serial No. 672,325

6 Claims. (Cl. 200—159)

This invention relates to electric switches and has special reference to that type of switch which is used principally in automobiles for establishing a circuit through the starting motor of such vehicles.

Furthermore, the type of switch of the present invention is that in which a pair of studs are arranged in parallel and serve both as fixed contacts and as means for connecting sections of a conductor cable, the studs being in the path of a movable bridging contact.

In switches of this type the two studs above referred to are necessarily, because of limitations in space for installing the switch and of manufacturing requirements, quite close together. There is thus danger of arcing or short circuiting between these studs or terminals and there is also danger, when applying the conductors, of bringing a conductor terminal accidentally into contact with both studs. Devices have been used to obviate these dangers by placing a wall of insulating material between the projecting ends of the studs. Such studs are held to the switch casing by nuts on the outside and a strip of insulating material has been used to form this wall by securing the ends on the studs beneath the nuts and looping the center of the strip to extend between the studs. This arrangement is open to the objection that the fastened ends of the necessarily thin strip are exposed to injury and may break off.

One important object of the invention is to provide an improved form of switch wherein the insulation between the studs or terminals is anchored within the switch casing in a novel manner.

The movable contact in this type of switch commonly consists of a rigid bar of conductive material and, in order to ensure contact with both studs, such bars have been loosely mounted on their carrying plungers to allow them to adjust to proper stud contacting position. Such loose mounting is objectionable because of the tendency to wear and become too loose and for other reasons.

A second important object of the invention is to provide, in such a switch, a novel arrangement of movable contact immovably mounted on its plunger but highly flexible for proper contacting of the fixed contacts while its cross-sectional area is ample to carry the amperage used without interfering with the flexibility.

With the above and other objects in view, the invention consists in general of certain novel details of construction and combinations of parts

hereinafter fully described, illustrated in the drawing and specifically claimed.

In the accompanying drawing like characters of reference indicate like parts in the several views, and,

Figure 1 is a vertical section through a switch constructed in accordance with this invention with the upper part of the plunger and casing omitted.

Figure 2 is a bottom plan view of the switch.

Figure 3 is a top plan view of the lower part or body of the casing and showing the fixed contacts therein;

Figure 4 is a bottom plan view of the upper part or cover of the casing and showing the movable contact.

Figure 5 is a perspective view of the novel arrangement for forming an insulating wall between the studs.

Figure 6 is a view of the blank from which the interior insulation of the casing is formed.

Figure 7 is a detail section on the same plane as Figure 1 but showing a modified form of movable contact.

In the invention as here disclosed there is provided a two part casing having a rectangular body 10 provided with a bottom and side walls and having a substantially hexagonal securing flange 11 extending from the upper edges of said side walls. The upper or cover part of this casing consists of a substantially hexagonal plate 12 provided with a depending peripheral flange 13 so that the flange 13 may fit around the edges of the flange 11. Tabs 14 are provided on the flange 13 which are rebent as in Figure 1 to secure the two parts of the casing together. On the plate 12 is a tubular plunger housing 15.

Within the body of the casing is fitted a one-piece insulating lining formed from a sheet of insulating material having a rectangular center portion 16 and side wall portions 17 (see Fig. 6) defined from the center by fold lines 18. These side wall portions are bent up so as to form an open topped box which is fitted in the body of the casing, as shown in Figure 1. In the central part or bottom of this lining is formed a pair of stud holes 19 which register with a similar but slightly larger pair of stud holes 20 formed in the bottom of the body 10. Threaded studs 21 extend through these stud holes and are provided interiorly of the casing with heads 22 which rest against the insulation. On the projecting portion of each stud is fitted an insulating washer 23 against which bears a clamping nut 24. Formed centrally between the holes 20 in the casing is a slot 24'. 55

A strip of insulating material is doubled to form a loop or bight 25 and has its legs extending through the slot 24' and bent laterally to provide feet 26 which lie between the insulation 16 and the bottom of the casing. Thus the feet 26 are clamped by the action of the nuts 24 between the insulation 16 and casing bottom within the casing free from accidental injury, and the loop forms a wall between the outer ends of the 10 studs. The usual binding nuts 27 and washers 28 are provided on these studs for securing cable ends.

Slidable through the top 12 centrally thereof is a plunger 29 preferably non-rotatable, urged to 15 protruded position by a spring 30. On this plunger is mounted a spring contact member 31 formed of a plurality of thin plates or laminations and, as shown in Figure 1, the upper of said plates may have its ends curved down to brace the lower 20 plates against too ready yielding. However, as shown in Figure 7, this upper plate may be omitted. The laminations are held between washers 32, and the end of the plunger is riveted over on the lower washer to solidly secure the parts 25 together. The plunger itself may be of insulating material or certain of the washers may be used to insulate the contact from the plunger. With a contact thus formed the movable contact member proper will readily yield to properly engage the 30 fixed contacts while, at the same time, it is immovably fixed to the plunger.

It will be noted that the laminations 31 are 35 preferably made about .02 of an inch in thickness. Furthermore, the upper lamination with its curved ends, as in Figure 1, is preferably made of stiff brass, while the other laminations are preferably made of phosphor bronze. By reason of this construction, this stiff brass acts to reinforce 40 and hold the phosphor bronze laminations.

It will also be noted that the one piece insulator, 45 with its sides extending up alongside of the sides of the casing, acts to guide the movable contact properly into engagement with the fixed contacts. Furthermore, the insulator being in one piece and the holes 19 being fixedly spaced, the threaded 50 fixed contacts may be mounted in this insulator and then the pair of contacts assembled with the casing by slipping through their openings 20, thus enabling the assembling of the device to be rapidly done. Finally it will be seen by the manner 55 in which this one piece insulating member bridges across the feet 26 of the separator 25, that it acts efficiently and positively to clamp the feet in position and also assists in the rapid assembling of the device.

There has thus been provided a simple and efficient device of the kind described and for the purposes specified.

It is obvious that changes may be made in the 60 form and construction of the invention without departing from the material principle involved. It is not therefore desired to confine the invention to the exact construction herein shown and de-

scribed, but it is desired to include all such as properly come within the scope claimed.

What is claimed is:

1. In a switch of the kind described, a casing 5 provided with a wall having a slot therein, a pair of contact studs extending through said wall on opposite sides of the casing, an insulating separator extending through the slot between the projecting portions of the studs, and means within the casing anchoring said insulating separator in 10 position.

2. In a switch of the kind described, a casing 15 provided with a wall having a slot therein, a pair of contact studs extending through said wall on opposite sides of the casing, an insulating separator extending through the slot between the projecting portions of the studs, flange means on said insulating separator within the casing and resting against said casing wall, and means to clamp the flange means in position. 20

3. In a switch of the kind described, a casing 25 provided with a wall having a slot therein, a pair of contact studs extending through said wall on opposite sides of the casing, an insulating separator extending through the slot between the projecting portions of the studs, flange means on said insulating separator within the casing and resting against said casing wall, heads on the inner 30 ends of said studs, and a plate secured by said heads and engaging said flange means to clamp the latter in position.

4. In a switch of the kind described, a casing 35 provided with a wall having a slot therein, a pair of contact studs extending through said wall on opposite sides of the slot, a strip of insulation doubled to form a loop extending between the projecting portions of the studs, the ends of the strip passing through the slot and extending laterally against said wall to form feet, and means to anchor said feet in position against said wall. 40

5. In a switch of the kind described, a casing 45 provided with a wall having a slot therein, a pair of contact studs extending through said wall on opposite sides of the slot, a strip of insulation doubled to form a loop extending between the projecting portions of the studs, the ends of the strip passing through the slot and extending laterally against said wall to form feet, and a clamping device engaging over said feet and secured within 50 the casing. 55

6. In a switch of the kind described, a casing 55 provided with a wall having a slot therein, a pair of contact studs extending through said wall on opposite sides of the slot, a strip of insulation doubled to form a loop extending between the projecting portions of the studs, the ends of the strip passing through the slot and extending laterally against said wall to form feet, said studs having heads within the casing, and an insulating member engaged beneath said heads and extending over the feet to clamp the feet in position. 60
